(57) **CLAIM**

The ornamental design for a display screen with animated graphical user interface, as shown and described.

DESCRIPTION

FIG. 1 is the first image in a sequence of a display screen with animated graphical user interface showing our new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof; and,

FIG. 8 is the eighth image thereof.

The appearance of the animated graphical user interface sequentially transitions between the images shown in FIGS. 1-8. The process or period in which one image transitions to another forms no part of the claimed design. The broken lines illustrate a display screen and form no part of the claimed design. The broken lines illustrate portions of the animated graphical user interface and form no part of the claimed design.
